UNITED STATES PATENT OFFICE.

GEORGE D. SLAYMAKER, OF DETROIT, MICHIGAN, ASSIGNOR TO SLAYMAKER ELECTRIC WELDING COMPANY, OF DETROIT, MICHIGAN, A CORPORATION OF MICHIGAN.

TROLLEY-WIRE FROG AND CROSSOVER.

Original No. 1,445,855, dated February 20, 1923, Serial No. 528,592, filed January 12, 1922. Application for reissue filed October 20, 1924. Serial No. 744,859.

To all whom it may concern:

Be it known that I, GEORGE D. SLAYMAKER, a citizen of the United States of America, and residing at Detroit, in the county of Wayne and State of Michigan, have invented certain new and useful Improvements in Trolley-Wire Frogs and Crossovers, of which the following is a specification.

10 This invention relates to trolley wire frogs or switches, and cross-overs, and has for its object a trolley wire fixture provided with adjustable runners which are renewable whenever this is deemed expedient.

15 This fixture is also provided with a removable pan which consists of a wear piece between the runners and is easily removed without renewing the entire device. Furthermore, the runners and pan are supported below the main plate so that the runners and pan may be easily removed from the plate without in any way disturbing the support of the plate upon the guy wires and poles. This is an important feature as these guy wires are always under a certain prescribed tension and it is very inconvenient and troublesome to remove the entire frog and replace it. By the arrangement of my runners it is possible to remove 20 both the runners and the pan without in any way disturbing the support of the frog upon the guy wires.

Another feature of my invention is the adjustability of the runners with respect to one another. The two movable or spur runners shown in the frog illustrated can be swung around on the main supporting plate, each through a considerable arc, yet always remain in position, which permits 25 the trolley wheel to travel from the stationary runner to either of the spur runners, or vice versa, depending of course upon the path taken by the car beneath. This permits the use of a single type of fixture for 30 various angularities of the spur line with respect to the main line and hence it is not necessary to have numerous patterns or dies to take care of all desired angles.

In the drawings:

- 35 Fig. 1 is an inverted plan view of a frog.
 Fig. 2 is a side elevation of the same.
 Fig. 3 is a section on the line 3—3 of Fig. 1.

Fig. 4 is a section on the line 4—4 of Fig. 1.

Fig. 5 is a section on the line 5—5 of Fig. 4.

Fig. 6 is a section on the line 6—6 of Fig. 1.

Fig. 7 is a section on the line 7—7 of Fig. 1.

a designates the main supporting plate. To this is bolted the stationary or main runner *b* by bolts *c*. This main runner is shown in detail in Fig. 4. It will be seen that it is provided with an end piece *d* which is bolted to the body of the runner *e* by the bolts *f*. The trolley wire is clamped and crimped between the end piece and the body of the runner when the two are clamped together and thereby the trolley wire is firmly held to the runner and the channel sides of the end piece are hammered in upon the wire. The same construction is used in all the runners so far as clamping the body and the channel together, and crimping and pinching the trolley wire.

The spur or adjustable runners *g* are not clamped to the trolley plate the same way. They are carried on the radius arms *h* which have their centers at *i*, *i*. The runners and the runner points are somewhat offset from the main axes of the radius arms, as is clearly shown in Fig. 1. Each of the centers *i*, *i* is substantially on a perpendicular line through the point of the stationary runner *b*—perpendicular to the axis of the stationary runner. Each of these centers is as close on either side of the point of the main runner as is feasible and still allow the radius arms to be cleared by the flanges of the trolley wheel. This results in the points of the swinging or spur runners swinging on arcs approximating an arc whose center is at the point of the main runner. For all practical purposes this arrangement of the radius arms with the offset swinging runners works just as well as though the points of the swinging runners did actually swing on an arc whose center was at the point of the main runner.

The main plate is provided with a pair of segmental slots *j* through which engage the bolts *k* by which the swinging runners may be clamped tightly in any given position of adjustment. The main plate *a* is somewhat

segmental in form and is provided at the four corners *m* with perforations to receive the guy wires.

It will be apparent that the main or stationary runner can be removed by loosening and removing the bolts *c* while the swinging runners can be removed by taking out the bolts *k* and the pivot bolts *i*. The pivot bolts *i* also in connection with the bolts 10 *n* serve to hold the pan or the wear plate *o* in place. Hence this pan may be easily removed when it wears out. All these adjustments and removals can be made without in any way altering the support of the main 15 plate upon the guy wires.

In Fig. 3, the clamp for the trolley wire is shown. One trolley wire passes out through the opening in the top of the main runner across the top of the supporting 20 plate and through the center blocks *x* into one of the adjustable runners. The other wire passes out of the adjustable runner and into one of the clamping blocks and the end is then usually turned around and used 25 as a guy wire to one of the poles. The clamping blocks are forced down against the wires by the nuts *z* engaging against the clamping bars.

I have illustrated my invention in connection with a trolley wire frog, but obviously the same is adapted for a crossing, or cross-over construction, with a few minor modifications which will be obvious.

What I claim is:

1. A trolley wire fixture, having in combination a main plate, and one or more runners removably secured to the under side of the main plate and comprising each a body portion and an end piece clamped together 40 to hold the trolley wire to the runner.

2. A trolley wire fixture, having in combination a main plate, a plurality of runners removably secured to the under side of the main plate, and a wear piece secured to the under side of the main plate and removable 45 when the said runners have been removed from the main plate.

3. A trolley wire fixture, having in combination a main plate, a plurality of runners bolted to the under side of the main plate so the same can be removed without disturbing the supports of the main plate, and a wear piece secured to the under side of the main plate and which can be removed when the runners are removed 55 without disturbing the supports of the main plate.

4. A trolley wire fixture, having in combination a main plate, a main runner supported on the said plate, and one or more swinging runners supported on the main plate and adjustable on arcs which approximate a coincidence with respect to an arc whose center is at the point of the main runner.

5. A trolley wire fixture, having in combination a main plate, a stationary or main runner supported on the main plate, and one or more swinging or adjustable runners supported on a radius arm on arms which have their center or centers closely adjacent the side or sides of the point of the main runner but sufficiently spaced to permit clearance for the flanges of the trolley wheel.

6. A trolley wire fixture, having in combination a main plate, a main runner supported by the same, and a swinging or adjustable runner supported on a radius arm whose center is closely adjacent at one side of the point of the main runner, the swinging runner being offset at one side of the radius arm so that the point of the swinging runner in swinging through an arc approximates an arc whose center would be at the point of the main runner.

7. A trolley wire fixture, having in combination a main supporting plate provided with a segmental slot, a main or stationary runner supported on the under side of said plate, a radius arm supported adjacent the point of said runner on a pivot, a swinging runner supported on said radius arm at one side thereof so that the point of said swinging runner approximates an arc whose radius would have its center at the point of the main runner, and a bolt passing through said radius arm and through said segmental slot in the main plate for adjustably securing said swinging runner on the said main plate.

8. A trolley wire fixture, having in combination a main plate, a stationary runner supported on the main plate, a removable wear piece or pan bolted to the under side of the main plate, a radius arm bolted through the main plate at a point closely adjacent the point of the main runner but at one side thereof, and a swinging runner supported on said radius arm at one side thereof, and in such a way that the point of the runner in swinging upon the pivot of the radius arm swings through an arc approximating an arc whose radius would have its center at the point of the main runner.

9. A trolley wire fixture, having in combination a main plate, a stationary runner supported on said plate, and one or more angularly adjustable runners supported on the main plate and each bodily adjustable independently of any other runner on a swinging radius having its center beyond the point of the runner and near the point of the stationary runner.

10. A trolley wire fixture, having in combination a main plate provided with one or more segmental slots, a stationary runner supported on said plate, one or more angularly adjustable runners, each of which is

5 bolted to said plate through a segmental slot and adjustable with respect to the stationary runner by loosening the bolting means and moving and bolting the runner again through said segmental slot, said adjustment being only on a swinging radius having its center beyond the point of the adjustable runner and near the point of the stationary runner.

10 11. A trolley wire fixture, having in combination a main plate provided with one or more segmental slots, a stationary runner removably supported on said plate, one or more angularly adjustable runners, each of which is removably bolted to said plate through a segmental slot and may be removed from said plate without disturbing its support, the said adjustable runner being angularly adjustable with respect to the stationary runner by loosening the bolting means and moving the runner and then again tightening the bolting means, said ad-

justment being only on a swinging radius having its center beyond the point of the adjustable runner and near the point of the stationary runner.

12. A trolley wire fixture, having in combination a main plate provided with one or more segmental slots, a stationary runner removably supported on said plate, one or more angularly adjustable runners, each of which is removably bolted to said plate through a segmental slot, and angularly adjustable with respect to the stationary runner by reason of said bolt and slot connection with the main plate, and a wear plate removably bolted to the under side of said main plate and removable with the runners without disturbing the support for the main plate.

35 In testimony whereof, I have hereunto affixed my signature.

40 GEORGE D. SLAYMAKER.
